UNITED STATES PATENT OFFICE.

ALFRED S. EMERSON, OF LONDON, ENGLAND.

SNOW-MELTING MACHINE.

No. 888,979.

Specification of Letters Patent.

Patented May 26, 1908.

Application filed January 6, 1908. Serial No. 409,441.

To all whom it may concern:

Be it known that I, ALFRED S. EMERSON, a citizen of the United States, residing at London, England, have invented certain new and useful Improvements in Snow-Melting Machines, of which the following is a specification.

This invention relates to street cleaning apparatus, and more particularly to a device for removing the snow from the street and for melting the same.

The invention has particular reference to the mechanism for scraping up the snow from the street and conveying this into a receptacle which is in the form of a tank and to the furnace mechanism for heating this tank for reducing the snow to water.

In the drawings accompanying and forming a part of this specification Figure 1 is a side elevation of a practicable embodiment of a form of my invention, certain of the side walls are broken away in this view to show the interior construction. Fig. 2 is a cross section of the device illustrated in Fig. 1, taken in about the center of this view. This view is somewhat enlarged over the showing in Fig. 1. And Fig. 3 is a detail of the left hand end of the tank and surrounding structures illustrated in Fig. 1. This view is mostly in vertical section, but taken on several planes, for instance the smoke stack is broken into, the tank, flue and fire boxes are shown beyond this, each broken into at a different plane.

The various operative parts are mounted upon and carried by a suitable carriage, designated in a general way by 7. At the front end of the machine there is mounted a hood 8 which may be pivoted to the body or receptacle portion 9 and within this is mounted an endless belt 10 having a number of conveyer buckets 11. This endless belt will travel from a point near the road surface to a point within the receptacle where it will drop the snow which has been delivered to it by a scraper 12 which precedes the conveyer belt and scrapes the snow up and the snow will ride up on this scraper until it comes to a position where the conveyer buckets will be effective to receive it and convey it into the receptacle or tank. The tank is intimately associated with a furnace. In the present instance the furnace is made up of a number of furnace units, and each furnace unit is shown as comprising a fire chamber or fur-

nace chamber 13 having suitable grate bars 14. The roof of the furnace and the floor of the tank in the present instance constitute the same plate 15.

The flames and heat from the furnace will pass along this floor 15 heating the water which may be above it, will pass on into the flue portion 16, the roof of which also constitutes the floor of another portion of the tank and is embodied in the plate 17. The various furnace chambers are separated by walls 18 of resistant material, but the flue portions are separated by means of side walls 19 of the tank and between which side walls is a space 20 which may receive water. The water in the immediate vicinity of the walls of the furnace chamber and of the flues will be raised to a high temperature and will form steam which will assist in the melting of the snow and the heating of the water from the snow which has been melted.

A pocket or mud drum 21 is provided at the rear of the furnace chamber in the tank and into this will settle such mud as may be taken up with the snow. This may be let out through a suitable vent 22 from which vent water will also be ejected, when the device may be drawn up to a sewer opening and emptied there or any convenient place which may be chosen. The water, of course, coming out at a high temperature will have an opportunity to escape into the sewer before again freezing. By having this mud receptacle the mud will be kept away from those walls of the tank through which the heating of the water is effected and by this means the mud will not be permitted to insulate the heating walls. This mud pocket or drum is shown as having considerable area at the position 23, which is immediately below the point of delivery of the conveyer belt. By this means the mud carried in with the snow will immediately sink into the drum without being carried into the portions of the tank where it will foul the heating surfaces.

The perforated pipe 25 is located at a point where the horizontal flue 16 turns into the vertical smoke stack 26. The small arrows 27 indicate the passage of the unconsumed portions of fuel and gases which will travel along the upper part of this horizontal portion of the flue and find ready entrance into the perforations of the pipe 25 and will be drawn down the pipe 27 by means of the steam injector 28 and will be discharged be-

low the furnace grates and be passed through the fire by means of the draft of the fan 29 which may be driven in some convenient manner, as for instance by means of a steam 5 turbine.

When it is desired to raise the scraper for any purpose, as for instance, to change its position of working or to put it in an inoperative position a hand lever 31 near the driver's 10 seat 32 may be actuated, which by means of a connecting bar 33 will act on the long end of a lever 34 which is linked at 35 to the hood 8 and will thus raise the hood and scraper or lower the same as occasion may demand.

15 The floor 24 of each of the horizontal flues constitutes the roof plate of a portion of the tank. The portions 35 of the tank are in the nature of boiler tubes.

Having described my invention I claim:

20 1. The combination with a furnace grate, fire chamber and furnace flue, of a tank surrounding said flue and having a floor which constitutes the roof of the fire chamber, means for scraping up snow, and means for

conveying the snow to said tank, and a carriage upon which the same is mounted. 25

2. The combination with a plurality of independent furnaces, each comprising a grate, a fire chamber and a furnace flue, of a tank surrounding said flues, the walls of which 30 constitute the sides of said flues being separated between the adjacent flues to leave a space for water, said tank having a floor which constitutes the roof of the fire chamber, and portions of which constitute the roof and floor 35 of each of the flues, a smoke stack communicating with all of the flues, a blower for each of said grates, and means for removing snow from a road surface and conveying the same to said tank, and a carriage upon which the 40 same is mounted.

Signed at Nos. 9-15 Murray street, New York, N. Y., this 13th day of December, 1907.

ALFRED S. EMERSON
